UNITED STATES PATENT OFFICE.

BERNHARD R. KIESSIG, OF CHICAGO, ILLINOIS, ASSIGNOR TO THE AMERICAN MUSIC COMPANY, OF CHICAGO, ILLINOIS, A CORPORATION OF ILLINOIS.

MUSICAL INSTRUMENT.

SPECIFICATION forming part of Letters Patent No. 752,782, dated February 23, 1904.

Application filed May 19, 1903. Serial No. 157,763. (No model.)

To all whom it may concern:

Be it known that I, BERNHARD R. KIESSIG, a citizen of the United States, residing in the city of Chicago, county of Cook, State of Illinois, have invented a new and useful Improvement 5 in Stringed Musical Instruments, of which the following is a specification.

My invention relates to stringed musical instruments wherein the strings are struck by means of hammers operated by finger-keys; and the objects of my invention are, first, to provide an instrument-body which shall be light in weight and at the same time of great strength in resisting the tendency to collapse 15 under the tension of the strings; second, to provide a flexible connection between the key and the key-lever; third, to provide a self-adjusting damper; fourth, to provide connections between the key-lever and the hammer whereby a slight motion of the key will produce the necessary travel of the hammer; fifth, to produce a particular form of overthrow mechanism whereby the hammer may have an overthrow movement to strike the 25 sounding string and be immediately thereafter lifted from the string while the key is yet depressed and the damper held out of contact with the string; sixth, to produce a soft action, so that little force will be required to cause the string to sound; seventh, to provide the other details hereinafter more specifically set forth. I attain these objects by the mechanism illustrated in the accompanying drawings, in which—

Figure 1 is a plan view of the complete instrument, showing a portion of the hood broken away to reveal the rear portions of some of the key-levers. Fig. 2 is a transverse vertical section of the complete instrument, taken on line 2-2, Fig. 1. Figs. 3 and 4 are sectional views drawn to an increased scale to illustrate the key-action. In Fig. 3 the parts are shown in their normal condition with the hammer raised. In Fig. 4 the parts 40 are shown with the key depressed and the damper raised, while the hammer is shown in full lines to be raised from the strings in the position assumed immediately after the

string has been struck, but before the key has been released. The position of the hammer 50 shown in dotted lines, Fig. 4, indicates the time during the overthrow when the hammer strikes the string. Fig. 5 is a fragmentary detail view illustrating the connection between the key and the key-lever. Fig. 6 is a top 55 fragmentary view of a hammer and its adjacent operating devices.

Similar letters refer to similar parts throughout the several views.

The instrument-body comprises the sounding-board *a*, the wrest-plank *b*, the string-block *c*, and the thrust-pieces *d d*, which are arranged in the well-known manner.

The bottom *e* of the instrument is not constructed of wood, but consists of a sheet of 65 metal which extends between and is secured to the wrest-plank *b*, string-block *c*, and thrust-pieces *d*. By preference a fold *e'* is turned in the sheet-metal instrument bottom at the point where it is secured to the under surface of 70 the string-block *c*. The string-pins *e''* penetrate said double or folded portion of the instrument bottom and are rigidly held in the string-block *c*.

The string-rail *f* extends across the instrument above the sounding-board *a*, and the strings *f'*, which are rigidly secured at one end to said pins *e''*, extend around and over the outside of the block *c*, over the rail *f*, to the wrest-pins *f''*, mounted in the wrest-plank 80 *b*. By this construction, inasmuch as the pins *e''* penetrate the instrument bottom *e*, the strain due to the tension of the strings is transmitted over the string-block through the wrest-pins *f''* and instrument bottom *e* back 85 to the wrest-plank *b*—that is to say, the pins *e''*, which are held rigid in the instrument bottom *e*, as well as in the string-block *c*, serve as a positive connection between said instrument bottom and the strings *f'*, so that the 90 tightening of the strings also causes the tightening of the said instrument bottom. The advantage gained by this construction lies in the fact that the tension of the strings does not depend upon fastenings mounted in the string-block, but depends instead upon the pins *e''*, 95

which are retained by the instrument bottom itself. Thus when the strings f' are tightened the tendency is to draw the instrument bottom e tight, the strings slipping over the outer surface of the string-block c . Inasmuch as they are permanent fastenings which secure the instrument bottom to the wrest-plank b , there is less likelihood that there will be any give to said instrument bottom when the strings are brought up to pitch. By thus having the tension of the strings depend upon the security of the instrument bottom the entire instrument-body becomes rigid and prevents the strings from becoming slack, and hence losing their proper pitch.

The board g extends transversely to the keys at a slight distance above the strings and has the key-action mounted thereon. By preference said mount-board g is supported upon the blocks $g' g'$, as shown in Fig. 1. The key-levers h are mounted side by side and one above each of the strings e . The pins h' , mounted in the posts h^2 on the mount-board g , serve as fulcrums for said key-levers h . A returning-spring i is mounted in position to return the key-levers h to the normal position shown in Fig. 3.

It is desirable to provide a piece j , of leather, felt, or other suitable material, to relieve the shock when the key is returned to normal position under the influence of the spring i . In a similar manner leather, felt, or other material is interposed between the said key-levers and the lever-stop k .

The keys m are preferably cylindrical in form, or nearly so, and arranged to stand in an approximately vertical position.

In order that the keys may be readily operated and afford a pleasurable yielding sensation when touched by the performer, a flexible connection between the keys and key-levers is provided. By preference this connection consists of a piece of leather m' , extending partially into the key-lever h and partly into the key itself. As illustrated in Fig. 5, this permits a vibration of the key, which enables it to yield to the lateral movement of the fingers when struck. The best results are obtained when said piece m' is arranged with its width transverse to the key-lever, so that the greatest vibration is fore and aft—that is, in the direction of the length of the key-lever.

A hammer n is provided for each of the strings e and has any suitable configuration. The rods n' are secured at one extremity to the segments o and at the other extremity carry said hammers n . Said segments are revolvably mounted on the axles o' , supported in the brackets o^2 , and the arrangement is such that the rotation of such segments about their axes will move the hammer n toward or from the strings e . Said segments are rotated by means of the cords p , which are attached at one extremity to said segments by means

of the staples or other fastenings p' and are led thence around said segments and up to the hooked forward extremity of the substantially inflexible rods q , projecting from the key-levers h . It is desirable that the surface of said segments be grooved to receive and retain said operating-cords p .

Segments o are normally held by the springs r in such a position that the hammers will remain at their greatest distance from the strings—as, for example, in the position shown in Fig. 3. Said springs are attached at one extremity to the pins r' , which are rigidly fixed in and project from the segments o . The other extremity of said springs is attached to the forward extremity of the damper-levers s . Said levers are pivoted upon the fulcrum-pins s' , mounted in the posts s^2 , located in the present instance beneath the mount-board g . Said damper-levers are operated by means of the links t , which are pivoted at one extremity to said levers s and at the other extremity to the key-levers h in such relation that the depression of the key-lever will cause the damper-lever s to rise. Said mount-board g is provided with apertures t' , through which said links t pass.

The dampers u consist of leather, felt, or other suitable material for arresting the vibration of the strings to stop the sound and have a flexible connection to said levers s through the damper-leaf u' . Said damper-leaves are, by preference, flexible metallic springs having a bend u^2 at or near the point of attachment to the lever s . Said leaves u' thus yieldingly hold the dampers u in contact with the strings f' , and a slight variation in the position of said levers s will not cause the dampers to leave said strings. This is an important feature, inasmuch as it is not necessary to have a nice adjustment of the levers s , for the dampers u are to a slight extent independent of the position of said levers.

I would now call attention to another important feature of my invention—namely, the overthrow of the keys and the means by which it is accomplished. This feature will be apparent upon an explanation of the operation of the key-action. Under normal conditions the springs i will maintain the keys in the raised position, as shown in Fig. 3, the dampers u will be down upon the strings f' , and the hammers n will be held at their farthest point from the strings. Now if the keys m be depressed very slowly the dampers u will be raised and the rods q at the forward extremity of the key-levers h will also be raised. The slow raising of the rods q will cause the segments o to rotate about their axes o' against the influence of the spring r until such time as the key-levers h come into contact with the stop k . The parts of the mechanism will then have reached the position shown in full lines in Fig. 4. In this position the hammer will

not be in contact with the strings *e*, but will be prevented from reaching said strings by reason of the tension of the springs *r*. This is when the keys *m* are depressed slowly. The 5 cord *p* is soft and flexible, and there is nothing except the springs *r* to hold the segments *o* from further rotation in a direction to lower the hammer onto the string. Under ordinary conditions, however, the keys are not depressed slowly, but are struck with greater or less force, as is common in performing upon key instruments of this class.

Under ordinary conditions of striking the key the hammers *n* will acquire such momentum that they will not stop at the moment when the key-levers reach the stop *k*, but will continue their motion toward the strings against the resistance of the tension-springs *r*. The hammers will thus reach the strings, 15 and the force with which said hammers strike them will determine the volume of the resulting sound. A light touch of the key will result in the production of a light tone, while a sharp stroke upon the key will produce a loud 20 tone upon the string. As soon as the hammer has struck the string it immediately rebounds, being acted upon both by the resiliency of the stretched string and by the tension of the spring *r*. If the key remains down, the damper *u* will remain raised; but the hammer *n* will also remain partially raised in the position shown in Fig. 4, so that the string will 25 continue to sound.

Another feature of my invention is concerned with the manner in which the spring *r* is mounted. It will be noted that as the pin *r'* rises it lowers the hammer, and the forward 30 extremity of the damper-lever *s* also rises. I prefer to so proportion the parts that the tension-spring *r* will not commence to be elongated until after the key-lever *h* has come to rest upon the stop *k*. Under such conditions the spring *r* may be extremely light and soft, only requiring sufficient strength to prevent 35 the hammer from dropping onto the string. The motion of the hammer toward the string after the key-lever has reached the stop *k* I term "overthrow," and it is preferably during this overthrow that the spring *r* is extended. It is well known that a helical spring 40 lasts longest when operated within limits near its normal length. By having the spring *r* thus attached to the part which follows the motion of the pin *r'* on the segment said 45 spring is not stretched or elongated to any such extent as it would be if attached to a fixed part of the device.

In the finished machine a hood *v* is placed over the key-levers and is apertured to permit the keys *m* to project up through the same, as best indicated in Figs. 1 and 2.

I do not wish to be understood as limiting myself to the precise proportions and relationship of the parts as herein shown, the es-

sential features of my invention being pointed out in the accompanying claims.

What I claim as new, and desire to secure by Letters Patent, is—

1. In a musical instrument, the combination with sounding-strings, of a body having 70 a metallic bottom connected at one edge to the wrest-plank and at the other edge to said strings.

2. In a musical instrument, the combination of a wrest-plank; a pin-block; sounding- 75 strings and a metallic bottom piece, said strings being connected at one extremity to the wrest-plank, and at the other extremity to said bottom piece, said strings passing over said pin-block and said bottom piece being attached to said wrest-plank.

3. In a musical instrument, the combination of a wrest-plank; a pin-block; thrust-pieces connecting the same; a sheet-metal bottom piece connected to said wrest-plank upon 85 one surface thereof; and sounding-strings connected to said wrest-plank on another surface thereof, said strings passing over said pin-block and being secured to said bottom piece at said pin-block.

4. In a musical instrument, the combination of a body-frame; sounding-strings and a sheet-metal bottom piece, said strings and said bottom piece being connected together near one edge of the instrument-body, and being 95 also connected to said instrument near the other edge thereof.

5. In a musical instrument, a key-action comprising an oscillating hammer; a damper-lever; a spring connected at one end to said 100 lever and at the other end to said hammer, and means for moving said damper-lever and said hammer simultaneously.

6. In a musical instrument, a key-action comprising an oscillating hammer; a damper-lever; a spring connected at one end to said lever and at the other end to said hammer; and a key-lever connected to said hammer and to said damper-lever to move said hammer and said damper-lever simultaneously.

7. In a musical instrument, a key-action comprising an oscillating hammer; a damper and damper-lever whereon said damper is carried; a spring connected at one end to said lever and at the other end to said hammer; 115 and a key-lever connected to said hammer and to said damper-lever for moving said hammer and said damper-lever simultaneously.

8. In a musical instrument, a key-action comprising an oscillating hammer; a damper; a damper-lever; a flexible connection between said damper and said damper-lever; a spring connected at one end to said lever and at the other end to said hammer; and a key-lever connected to said hammer and to said damper-lever for moving said hammer and said damper-lever simultaneously.

9. In a musical instrument, a key-action

comprising a pivoted hammer-segment; a key-lever; a flexible connection such as a cord wrapped upon said segment and attached at one end thereto and at the other end to said key-lever; a damper-lever; and a link connection between said damper-lever and said key-lever.

10. In a musical instrument, a key-action comprising a pivoted segment; a hammer-rod extending in one direction therefrom and carrying a hammer; a pin in said segment extending therefrom in a direction away from said hammer-rod, a lever, as *s*, and a spring connected at one end to said pin and at the other end to said lever, and means for moving said lever and said segment simultaneously to reduce the strain on said spring.

11. In a musical instrument, the combination of a body-frame; sounding-strings; a sheet-metal bottom piece, said strings and said bottom piece being connected together near one edge of the instrument-body and being also connected to said instrument-body near the other edge thereof; a key-lever; a hammer operated by said key-lever; and a damper operated by said key-lever.

12. In a musical instrument, the combination of a body-frame; sounding-strings; a sheet-metal bottom piece; said strings and

said bottom piece being connected together near one edge of the instrument-body and being also connected to said instrument-body near the other edge thereof; a key-lever; a hammer operated by said key-lever; a damper-lever operated by said key-lever; and a spring connected at one end to said hammer and at the other end to said damper-lever, said hammer and said damper-lever moving simultaneously, the point of attachment of said spring to said damper-lever moving simultaneously with and in the same direction as the point of attachment of said spring to said hammer.

13. In a musical instrument having a vibrating part for the production of sound, the combination of a key-lever having a limited throw; a pivoted hammer normally out of contact with the vibrating sounding part of the instrument; a segment secured to said hammer concentric with the pivot thereof for operating said hammer; a cord wrapped upon said segment, one end of said cord being attached to said segment and the other end of said cord being unyieldingly connected to said key-lever.

BERNHARD R. KIESSIG.
